UNITED STATES PATENT OFFICE

110,180

DESIGN FOR A MEDICINE BOTTLE

Charles d'Orville Pilkington Jackson, Edinburgh, Scotland, assignor to T. & H. Smith Limited, Edinburgh, Scotland, a British company

Application January 17, 1938, Serial No. 74,334

Term of patent 14 years

To all whom it may concern:

Be it known that I, Charles d'Orville Pilkington Jackson, a subject of the King of Great Britain, residing at 12 Church Lane, Edinburgh, Scotland, have invented a new, original, and ornamental Design for a Medicine Bottle, of which the following is a specification, reference being had to the accompanying drawing, forming part thereof.

Fig. 1 is a plan view, Fig. 2 an elevation looking on one corner, and Fig. 3 an elevation looking on one side of a medicine bottle, showing my new design.

I claim:

The ornamental design for a medicine bottle, as shown.

CHARLES d'ORVILLE PILKINGTON JACKSON.
